NOTEBOOK HOLDER

Filed Sept. 4, 1930

*Inventor,
Margaret M. Wright,*

By George H. Snader, Atty.

UNITED STATES PATENT OFFICE

MARGARET M. WRIGHT, OF LEWISTON, NEW YORK

NOTEBOOK HOLDER

Application filed September 4, 1930. Serial No. 478,753.

My present invention relates to note-book holders and more particularly to holders adapted to receive a filler, as a stenographic note-book.

- 5 An object of my invention is to provide a note-book holder of simplified construction into which a filler may be inserted and from which said filler may be removed with a minimum of effort.
- 10 A further object of my invention is to provide a note-book holder adapted, in one position, to support the note-book in a tilted position whereby the contents thereof are visible and are supported in a convenient position for reading or transcribing.

Other objects, features and advantages will be apparent as the description proceeds.

- A better understanding of my invention may be had by reference to the drawings 20 wherein I have illustrated one form of my invention and wherein—

Figure 1 is a sectional view of a note-book embodying my invention, the note-book being illustrated in the horizontally extended position.

Figure 2 is an isometric view of the same, showing the positions occupied by the various parts thereof when said holder is in the tilted position, and

30 Figure 3 is an isometric view showing the holder in the closed position.

Referring to the drawings, in the form of my invention illustrated, reference numeral 10 designates generally a note-book holder comprising three sections, 11, 12 and 13, adapted to form the front and back covers and bottom or base portion thereof, respectively. Each section comprises a rectangular member 14 of heavy paper-board or other suitable material, completely covered by a continuous wrapper 15, which is preferably a heavy textile material of the nature of that ordinarily used as a binding material for books, and which may be secured to the sections 14 by an adhesive. As will be seen in

Figure 1, sections 11 and 13 are spaced from each other and are flexibly connected together by portions 15—a of wrapper 15, which extends therebetween. In a somewhat similar manner the portions 15—b of member 15 50 serves as a flexible connection to secure sections 11 and 12 together. However, portion 15—b is larger than portion 15—a and between the two layers thereof there is secured by means of an adhesive, a spring member 16 55 of substantially triangular cross-section. The adjacent surfaces of the two layers of portions 15—a and 15—b are secured together in any suitable manner, as by gluing or stitching. A tubular member 17 is secured to the under side of section 13 (Fig. 1) at the free end thereof. As shown, member 17 is inserted between section 13 and wrapper 15 and is held in position by an adhesive.

To insert a filler in the holder, sections 11 and 12 are moved downwardly, looking at Figure 1, until the adjacent ends thereof contact with the upstanding legs 16—a of spring 16. Upon further movement of said sections, the lower portion of said spring will act as a fulcrum, and the adjacent ends of sections 11 and 12 will move away from each other, thus separating the upper free ends of legs 16—a and permitting of the insertion therebetween of a filler. Upon releasing sections 70 11 and 12, legs 16—a will move toward each other until they engage that portion of the filler positioned therebetween and will hold the latter firmly in position within the folder. For writing purposes the holder is placed in the position shown in Figure 3 and front cover 11 is folded back. In the reading or note-transcribing position, illustrated by Figure 2, the lower free end of cover 11 rests against cylindrical member 17, the latter member serving as a stop to prevent sliding movement of said lower end in a horizontal direction and thus maintains covers 11 and 12 in the position illustrated.

The advantages of my invention will now 90

be apparent. The holder may be quickly filled by bending cover members 11 and 12 in the manner described and inserting the filler between the separated free edges of 5 spring 16. No adjustment for different size fillers is necessary. The conventional stenographic note-book which is generally provided with a heavy paper cover, may be readily used by removing the cover from one side 10 thereof, leaving only a portion sufficiently long to be inserted between the upper free edges of spring 16, as indicated in broken line in Figure 2.

It will be found that by using a piece of 15 the cover of the note-book as a flap in this manner, the note-book will lie perfectly flat against cover member 11.

A further advantage of the holder described lies in the fact that when occupying 20 the position shown in Figure 2, it will remain perfectly stationary and will not be moved or caused to "walk" by vibrations such as those incidental to the operation of a type-writer.

25 Tubular member 17, in addition to functioning as a stop for cover 11, also serves as a pencil holder.

I have described and illustrated one form 30 of my invention. Many modifications will occur to those skilled in the art. I do not intend to be limited to the form described and shown, but intend this patent to cover all such modifications as fall within the scope of the appended claims.

35 What I claim as my invention and desire to secure by Letters Patent, is

1. A note-book cover comprising a front cover, a back cover and a base portion, a continuous strip of flexible material secured to 40 said covers and said base section, and pencil-holding means interposed between said fabric and the free end of said base portion.

2. A note-book holder comprising a front cover, a back cover spaced therefrom at one 45 end thereof, a base portion spaced from the opposite end thereof, a continuous strip of flexible material affixed to said covers and said base portion, the portions of said flexible material between said front and back 50 covers and said front cover and said base portion constituting flexible connectors therebetween, a spring positioned between the two layers of said flexible material interposed between said front and back covers and 55 adapted to be opened thereby, and a member inserted between said flexible material and the free end of said base portion and adapted to hold said front and back covers in triangular relationship with said base portion, 60 and to serve as a pencil holder.

3. A note-book holder comprising a cover member, a second cover member flexibly connected therewith at one end thereof, a base portion flexibly connected to said first-named 65 cover member at the opposite end thereof,

said two covers being adapted in one position to form a triangle with said base portion, a tubular member secured to the free end of said base portion and adapted to retain said cover in triangular formation with 70 said base portion, and a spring clip interposed between said two covers and adapted to be opened and closed by said covers to permit of the insertion and removal of a filler.

In witness whereof, I have hereunto subscribed my name.

MARGARET M. WRIGHT.
